United States Patent

Des. 239,093

Patented Mar. 9, 1976

239,093

CALIBRATED RULER

Albert Balla, Fort Lauderdale, Fla.
(2078 Integrity Drive N., Columbus, Ohio 43209)

Filed Oct. 11, 1973, Ser. No. 405,322

Term of patent 14 years

Int. Cl. D10—04

U.S. Cl. D10—71

The figure is a perspective view of a calibrated ruler, showing my new design.

The bottom of the ruler is plain and unornamented.

I claim:

The ornamental design for a calibrated ruler, as shown.
